UNITED STATES PATENT OFFICE

HUGO JUNKERS, OF DESSAU, GERMANY

SHEET-METAL CUTTER

Application filed October 5, 1925, Serial No. 60,696, and in Germany January 8, 1925.

- My invention refers to devices for cutting thin sheet metal and more especially corrugated or other profilated sheet metal in parallel to the corrugations or other profilations.
- 5 It is an object of my invention to simplify the cutting of such sheet metal by hand, to save time and to obtain a perfectly straight cutting edge extending strictly in parallel to the corrugation or the like.
- 10 The cutter according to this invention comprises a frame provided with a grip and having mounted at either end supporting and guiding rollers shaped to correspond to the corrugations or other profilations of the sheet metal.
- 15 The cutters are preferably mounted on the frame intermediate these supporting rollers. Preferably the lower cutter is exchangeably mounted on the frame while the upper cutter having the form of a disc forms one edge of a third roller guided in the corrugations or the like of the sheet metal, this third roller being preferably wider at right angles to the cutting direction than the guiding rollers and thereby increasing the lateral 50 stability of the tool during the cutting and further improving the accuracy of cutting.
- 20 The two supporting and guiding rollers are preferably arranged to run in one and the same corrugation of the sheet metal.
- 25 The novel tool can be adapted to the cutting of sheet metal having various profiles, but it is equally applicable to plane sheet metal. By correspondingly arranging the cutters any desired cutting level relatively 55 to the form of the profile can be obtained and owing to the circumstance that the distance from the cutting edge to any predetermined point of the profile remains the same throughout the cutting operation, no previous marking of the cutting line is required.
- 30 In the drawings affixed to this specification and forming part thereof a tool embodying my invention is illustrated diagrammatically by way of example. In the drawings—
- 35 Fig. 1 is a side elevation, Fig. 2 is a horizontal section on the line II—II in Fig. 1, and Fig. 3 is a vertical section on the line III—III in Fig. 1.
- Referring to the drawings, 1, 1 are the supporting and guiding rollers and 2 is the frame, at the ends of which these rollers are mounted, 4 being a grip forming part of the frame. The rollers 1, 1 are profilated to correspond to the corrugations 10 of corrugated sheet metal such as shown at the bottom of Fig. 3, these rollers being arranged to run in one and the same corrugation. On the top edge of frame 2 is exchangeably mounted the lower cutter 5. 6 is the intermediate roller 60 mounted on the frame, the edge 7 of the end face of this roller which adjoins the frame, forming a circular cutter cooperating with the lower cutter 5. 8 is the bracket supporting the spindle of roller 6, which latter is 65 wider than the rollers 1 and extends into a second corrugation of the metal sheet, as shown more especially in Fig. 3. When the tool is forced across the metal sheet in the direction of the arrow *a* in Fig. 1, with the 70 edge of the sheet inserted between the cutters, the circular cutter 7 will rotate and in cooperating with the stationary cutter 5 will cut the sheet in parallel to the corrugations. 75
- I wish it to be understood that I do not desire to be limited to the exact details of construction shown and described for obvious modifications will occur to a person skilled in the art.
- I claim:—
1. A device for cutting corrugated sheet metal comprising a frame, two circumferentially corrugated rollers with parallel axes mounted in line on said frame to support a cutter on and to space same relative to the metal sheet to be cut, a rotary cutting element on one of said rollers and a blade fixed to said frame in cooperative relation with said rotary cutting element and adapted to engage the lower face of the metal sheet. 80
- 85
- 90

2. A device for cutting corrugated sheet metal comprising a frame, two circumferentially corrugated rollers with parallel axes mounted in line on said frame to support a cutter on and to space same relative to the metal sheet to be cut, a third circumferentially corrugated roller between said two rollers, a rotary cutting element formed on said third roller and a blade fixed to said frame in cooperative relation with said rotary cutting element and adapted to engage the lower face of the metal sheet.

In testimony whereof I affix my signature.
HUGO JUNKERS.
